C. D. PLATT:
ELECTRIC SWITCH,
APPLICATION FILED MAR. 22, 1916.

1,234,211.

Patented July 24, 1917

UNITED STATES PATENT OFFICE.

CLARENCE D. PLATT, OF BRIDGEPORT, CONNECTICUT.

ELECTRIC SWITCH.

1,234,211.

Specification of Letters Patent. Patented July 24, 1917.

Application filed March 22, 1916. Serial No. 85,793.

To all whom it may concern:

Be it known that I, CLARENCE D. PLATT, a citizen of the United States of America, residing at Bridgeport, Connecticut, have 5 invented a new and useful Electric Switch, of which the following is a specification.

My invention relates particularly to what is commonly termed a combination switch having two hinged or knife-blade switch 10 members and sockets for two fuse plugs.

The main object is to reduce the size of the parts to a minimum within proper limits of electrical and mechanical safety.

In its preferred form the invention comprises an insulating base, two pairs of stationary switch terminals, a pair of short switch blades connected by an insulating handle extending across the blades above the contact jaws, and two fuse plug sockets with 20 converging bent connectors between the switch jaws and the center plug contacts.

Other details will be apparent from the drawings and the following specification.

Figure 1 is a plan view of the construction embodying the improvements of my invention, the switch being in the closed or "on" position.

Fig. 2 is a bottom view of the same.

Fig. 3 is a longitudinal sectional view and 30 side elevation on the plane of the line 3—3 of Fig. 1, showing the switch blades in the closed position in full lines and in the open or "off" position in dotted lines.

Fig. 4 is a perspective view of the switch 35 blades and handle.

The base 10 is constructed of porcelain or other suitable insulating material. The stationary hinge post 11 of the switch is suitably secured to the base and provided with 40 a circuit terminal 12. The jaw terminal 13 of the switch is also suitably secured to the base in line with the hinge terminal. The blade 14 is hinged to the post 11 preferably with a suitable friction connection and its 45 free end is adapted to engage between the jaws of the contact member 13, but preferably does not extend beyond the jaws.

The fuse plug screw socket 15 is secured to the base in any suitable manner and is 50 provided with a circuit terminal 16. The center plug contact 17 is connected to the jaw terminal of the switch 13 by means of a bent bar or connector 18 which extends from the back to the front of the base 55 through an opening as is customary in such constructions.

The screw sockets 15 are preferably partially surrounded by guard flanges 19 and the two flanges are connected by a web 20 which reinforces the parts. The two sockets 60 are preferably located as near together as possible, and the connectors 18 converge from the jaw terminals of the switch to the center terminals of the sockets.

The handle of the switch 21 is preferably 65 formed of insulating material such as vulcanized fiber and is preferably broad and provided with an opening 22 for the finger or fingers. The opposite ends of this handle are preferably riveted to lugs 23 projecting 70 outwardly from bracket portions 24 on the outer faces of the switch blades.

The construction will be seen to be very compact. The switch handle extending across the switch blades is readily accessible, 75 and is located in such a position that it is practically impossible for the operator to be affected by the arc when opening the circuit. The ends of the switch handle and the lugs 23 serve as stops to limit the movement of 80 the switch blades to the closed position, so that the closing action is uniform. The switch blades being much shorter than in the usual construction take up very much less room so that the entire construction can be 85 shorter. It will also be noted from the dotted line position of Fig. 3 that less space is required below the insulating block 10 than would be the case if the switch arms were longer, as in the usual construction. By 90 having the handle inclined and with a central opening, it is easier to take hold of the handle both in the opening and closing movements than it would be with a straight bar.

By reducing the size of the base both laterally and longitudinally, I have not only reduced the cost of the construction itself but reduced the cost of packing and the cost of shipment. This construction also materially reduces the storage space for stock 100 purposes and reduces the space required for installation.

It should be understood that the details of the switch blades and handle are valuable 105 improvements not confined to use in the particular relation herein shown; and further it will be seen that the invention is equally as well adapted to three pole as well as to double pole switches.

What I claim is:—

1. In a switch of the character described,

an insulating base, hinge posts mounted on said base, switch contacts on the base in line with the hinge posts, parallel switch blades pivoted at their base ends to said posts and disposed to engage the switch contacts with their free swinging ends, handle supporting lugs projecting outwardly from the edge portions of the blades near the free ends thereof, and a handle secured to said lugs and perforated to receive a member for operating the switch, said handle having a dependent part projecting between the switch contacts in the switch-closed position and forming a finger guard between the finger and said switch contacts.

2. In a switch of the character described, an insulating base, hinge posts mounted on said base, switch contacts on the base in line with the hinge posts, parallel switch blades pivoted at their base ends to said posts and arranged to engage the switch contacts with their free swinging ends, handle supporting lugs on the edge portions of the switch blades adjacent the free ends thereof, projecting laterally from the plane of the blades and inclined away from the free ends of the blades to form laterally disposed inclined seats for a handle, and an operating handle having substantially flat end portions bearing on said laterally projecting lugs and rigidly secured thereto and having a portion projecting between the switch contacts, when the blades are in the closed circuit position, to form a finger guard.

3. In a switch of the character described, an insulating base, hinge posts mounted on said base, switch contacts on the base in line with the hinge posts, parallel switch blades pivoted at their base ends to the hinge posts and arranged to engage the upstanding switch contacts with their free swinging ends and a handle secured to said switch blades at a point above the contacts when

the switch is closed and provided with a dependent intermediate portion between the switch blades extending in between the upstanding switch contacts in said switch-closed position.

4. In an electric switch, an insulating base, a pair of posts and circuit terminals secured at one end of said base, a pair of threaded fuse sockets and circuit terminals secured to the opposite end of said base, stationary switch contacts secured to said base between said posts and said sockets, the center of said fuse sockets being closer together than said contacts, converging connectors connecting said contacts and said fuse sockets, a switch blade pivoted at one end to each post and engaging at its opposite end with one of said contacts, an inclined insulating handle member secured to said switch blades between the ends thereof and above said contacts and having a passage for the finger between said contacts in line with the space between said fuse sockets, part of said handle serving as a guard to extend between said contacts and prevent the finger from coming in contact with live parts when the switch is closed.

5. In a switch of the character described, an insulating base, hinge posts mounted on said base, switch contacts on the base in line with the hinge posts, a pair of switch blades arranged side by side and pivoted at their base ends to the hinge posts and arranged to engage the upstanding switch contacts with their free swinging ends and a handle secured to said switch blades at a point above the contacts when the switch is closed and a guard means between the upstanding switch contacts to practically prevent the finger from engaging the same when dislodging said blades from said contacts.

CLARENCE D. PLATT.
